UNITED STATES PATENT OFFICE.

JOHN L. MAUCH, OF BROOKLYN, NEW YORK.

PROCESS AND APPARATUS FOR CASTING HOT LIQUID MATERIAL.

1,417,542.

Specification of Letters Patent. Patented May 30, 1922.

Application filed May 10, 1921. Serial No. 468,223.

To all whom it may concern:

Be it known that I, JOHN L. MAUCH, a citizen of the United States, residing at Brooklyn, in the county of Cook and State 5 of New York, have invented or discovered certain new and useful Improvements in Processes and Apparatus for Casting Hot Liquid Material, of which the following is a specification, reference being had therein 10 to the accompanying drawings.

This invention relates to the handling of hot liquid materials and especially, although not exclusively, to the cooling and solidification of molten sulphur.

It has heretofore been customary to cast molten sulphur in molds of a suitable form and size, but, by reason of the fact that the heat conductivity of sulphur is extremely 5 low, the time required for the sulphur to set 10 and solidify in the molds has rendered mold casting thereof extremely slow and objectionably expensive.

The present invention has for its object to provide a method and means whereby molten sulphur and other materials having similar properties may be quickly and inexpensively cooled and solidified and delivered in a convenient form for storage or further handling.

The foregoing and other objects of the invention, together with one mode of carrying the same into effect, will best be understood from the following description of the arrangement and operation of certain forms of apparatus illustrated in the accompanying drawings. It will be understood, however, that the particular constructions and operations described and shown have been chosen for illustrative purposes merely, and that the invention, as defined by the claims hereunto appended, may be otherwise practiced without departing from the spirit and scope thereof.

In said drawings:

Fig. 1 is a diagrammatic view of an apparatus arranged and operating in accordance with the invention.

Fig. 2 is a detail section on the line 2—2, Fig. 1.

Fig. 3 is a vertical sectional view of the material containing and depositing means, illustrating a modified construction.

Fig. 4 is a plan view of the container shown in Fig. 3 with the cover removed.

Referring to Fig. 1, the hot liquid sulphur 55 or other material from any suitable source is delivered through an inlet conduit 10 to a receptacle or container 11 having an overflow 12, whereby the liquid level in said container may be maintained substantially 60 constant. The container 11 is preferably formed with a double wall providing a heating jacket 13 which may be supplied, as at 14, with steam or other heating fluid, said container having a heat-insulating jacket 65 16, whereby the heat supplied thereto by the jacket 13 is retained. The container 11 is provided with one or more, but preferably a plurality of discharge outlets or nozzles 17 which preferably communicate with the interior of said container at different levels and extend through the heating jacket 13, which therefore serves to supply heat to said nozzles as well as to the body of the container. Screens 18 are preferably disposed 70 over the inlet 10 and outlets 17 in order to remove any foreign material and insure homogeneity of the material discharged from said container.

The material from the nozzles 17 is deposited upon a moving carrier in the form of a flexible belt 19 having an upper reach supported by idlers 20 in a position to receive said material. Said belt 19 passes about pulleys 21, 22 and 23, one of which may be positively driven by any suitable means (not shown) to cause said belt to travel in the direction indicated by the arrows, and one of which, preferably the pulley 23, may be a take-up pulley to keep slack out of the belt. 80

In accordance with the invention, the belt 19, or the material receiving surface thereof, is preferably composed of rubber or its equivalent, or of a suitable fabric impregnated with rubber or the like, so as to present a compact, non-fibrous, and preferably elastic surface to which, it is found, the hot sulphur will not adhere to an objectionable extent, if said surface be cooled and wetted prior to the deposit of the sulphur thereon. 95 To this end the lower reach of said belt is preferably arranged to pass through a water tank 24, or there may be provided a pipe 25 adapted to deliver water to the sulphur re- 100

ceiving surface of said belt preferably in the form of a spray, or, if desired, both the tank 24 and pipe 25 may be employed.

The nozzles 17 for depositing the liquid material upon the upper reach of the belt 19, when more than one of said nozzles are employed, are arranged in a series disposed parallel to the direction of travel of said belt or carrier in such a manner as to deposit the material from the container 11 upon said belt or carrier in successive layers. Each layer so deposited is cooled prior to the deposit of a succeeding layer by jets or blasts of a suitable cooling fluid, preferably air, delivered by pipes 27 located between the said nozzles and beyond the last nozzle in the series. Said nozzles 17 are formed with narrow discharge slots 52 disposed transverse to the belt 19 (see Fig. 2) so that the material is deposited on said belt in thin layers, which, together with the cooling effect of the air blasts from the pipes 27, and the precooling of that surface of the belt upon which the material is deposited by the water in the tank 24 and that supplied by the pipe 25, causes the sheet of material on said belt to cool throughout very quickly, so that, when said material is brought to the discharge end of the upper reach of the belt 30 adjacent the pulley 21, it will have become fully solidified.

As the belt passes about the pulley 21 it is drawn away from the sheet of solidified material, which it leaves readily by reason 35 of its initially wetted rubber surface, said sheet projecting beyond said pulley where it is struck by a series of centrifugal hammers 28 pivotally carried by a rotating shaft 29 disposed adjacent the pulley 21, said 40 sheet being broken by said hammers into pieces of convenient size which are permitted to drop into a suitably disposed hopper 30 or other receptacle.

In order to furnish a point of reaction 45 for breaking the sheet of solidified material leaving the belt or carrier 19, there may, if desired, be employed a weighted roller 31 carried by suitably pivoted links 32 and resting upon the material on the belt adjacent the pulley 21.

Any liquid material which may spill from the edges of the belt 19 may be caught by a suitably arranged trough 33 and delivered thereby to the tank 24, which constitutes a 55 sump for collecting such material. As herein shown the upper end of said trough is supplied with water through a pipe 26 which water serves to wash the material into said sump as well as to supply the tank 24.

60 In order to remove from the surface of the belt 19 any particles of material still adhering thereto after leaving the pulley 21, there is provided in the tank 24 a rotary brush 34 engaging the material receiving surface of 65 said belt, said brush also engaging a station-

ary cleaning bar 35, whereby the particles of material removed from said belt by said brush are disengaged from the latter.

In the arrangement shown in Figs. 3 and 4, the container 40 for the molten material is supplied by an inlet 41 under the control of a float valve 42, and said container is preferably provided with a heat insulating jacket 43 and cover 44, and is heated by suitable steam coils 45. The discharge openings of said container, which correspond in arrangement to the nozzle 17 shown in Fig. 1, comprise wells having dams 46, preferably formed with corrugated surfaces, and arranged with straight upper edges, which determine the effective position of the outlets, at substantially the liquid level controlled by the float valve 42. Within the container 40 adjacent each of said dams 46 is a rotating cylinder 47 mounted on a shaft 48 connected by suitable bevel gearing 49 with an actuating shaft 50 to which power is applied from any suitable source to rotate the cylinders 47. Said cylinders 47 are provided with flights or buckets 51, whereby the liquid material in the container is lifted over the edges of the dams 46 and permitted to flow in a thin stream upon the surface of the belt 19. The dams 46 may be disposed vertically, as shown, or at a slight forward inclination, if found desirable, in order to retain the material in the flights and cause the same to be spread evenly over the belt. In order to prevent the liquid material from running together at the lower edges of the dams, said edges may be serrated to correspond to the flights.

Having thus described my invention I claim and desire to secure by Letters Patent:

1. The herein described method of casting hot liquid material which consists in depositing said material in a thin layer upon a moving and previously wetted rubber-surfaced carrier, and thereafter artificially cooling said material.

2. The herein described method of casting hot liquid material which consists in depositing said material in a thin layer upon a moving and previously wetted rubber-surfaced carrier and thereafter blowing air upon said material to cool the same.

3. The herein described method of casting hot liquid material which consists in depositing said material in a succession of thin layers on a moving and previously wetted rubber-surfaced belt and thereafter artificially cooling said material.

4. The herein described method of casting hot liquid material which consists in cooling the surface of a moving and previously wetted, rubber-surfaced belt, and thereafter depositing said material in a thin layer upon said surface.

5. The herein described method of cast-

- ing hot liquid material which consists in depositing the same in thin successive layers upon a moving and previously cooled, and wetted, rubber-surfaced carrier.
- 5 6. The herein described method of casting hot liquid material which consists in depositing the same in thin successive layers upon a moving carrier, and in artificially cooling each of said layers prior to depositing 10 the next succeeding layer.
7. The herein described method of casting hot liquid material which consists in depositing the same in a layer or sheet upon the surface of a moving and previously 15 wetted, rubber-surfaced, carrier, permitting said sheet to cool and solidify, and thereafter breaking the same by impact.
8. An apparatus for casting hot liquid material comprising a moving, rubber-surfaced carrier, means for depositing said material upon said carrier, and means for previously wetting and cooling the surface of 20 said carrier before said material is deposited thereon.
- 25 9. An apparatus for casting hot liquid material comprising a moving, rubber-surfaced carrier, means for depositing said material upon said carrier, means for wetting said carrier before the material is deposited thereon, and means for directing a blast of air upon the material on said carrier.
10. An apparatus for casting hot liquid material comprising a moving, rubber-surfaced carrier and a plurality of devices disposed in a series arranged parallel to the 30 direction of movement of said carrier for depositing said material on said carrier in successive layers.
- 35 11. An apparatus for casting hot liquid material comprising a moving rubber-surfaced carrier, means for wetting said carrier, and a plurality of devices arranged in a series disposed parallel to the direction of 35 movement of said carrier and beyond said wetting means for depositing said material on said carrier in successive layers.
- 40 12. An apparatus for casting hot liquid material comprising a moving carrier, a plurality of devices arranged in a series disposed parallel to the direction of movement of said carrier for depositing said material thereon in successive layers, and means disposed between said devices for cooling each 45 layer prior to the depositing of a succeeding layer.
- 45 13. An apparatus for casting hot liquid material comprising a moving, rubber-surfaced carrier, a container for said material provided with means for discharging the same upon said carrier, means for wetting said carrier, and means for heating said container.
- 50 14. An apparatus for casting hot liquid material comprising a rubber-surfaced belt,
- a pulley over which said belt runs, means for wetting said belt, means for depositing said material upon said belt in the form of a layer or sheet, and means, disposed adjacent said pulley, for striking and breaking said sheet after solidification of the latter.
- 55 15. An apparatus for casting hot liquid material comprising a belt, a pulley over which said belt runs, means for depositing said material on said belt in the form of a layer or sheet, a shaft disposed adjacent said pulley, and centrifugal hammers carried by said shaft and adapted to strike and break the solidified sheet of material as said belt passes about said pulley.
- 60 16. An apparatus for casting hot liquid material comprising a moving, rubber-surfaced carrier, means for wetting said carrier, means for depositing said material on said carrier in the form of a layer or sheet, hammers for striking and breaking said sheet after solidification of the latter, and means for restraining the layers of material on said carrier against movement due to impact of the striking hammers.
- 65 17. An apparatus for casting hot liquid material comprising a moving, rubber-surfaced belt, a pulley about which said belt runs, means for wetting said belt, means for depositing said material on said belt, and a restraining roller disposed adjacent said pulley and adapted to engage the material on said belt.
- 70 18. An apparatus for casting hot liquid material comprising a moving, rubber-surfaced carrier, means for wetting said carrier, means for depositing said material on said carrier, and means for cleaning said carrier prior to the deposit of said material.
- 75 19. An apparatus for casting hot liquid material comprising a moving, rubber-surfaced belt, means for wetting said belt, means for depositing said material on said belt, a rotating brush co-operating with said belt for cleaning the same, and a stationary bar engaged by said brush, for cleaning the latter.
- 80 20. An apparatus for casting hot liquid material comprising a belt, means for depositing said material on said belt, a tank through which said belt runs, and a brush located in said tank and engaging said belt for cleaning the latter.
- 85 21. An apparatus for casting hot liquid material comprising a moving, rubber-surfaced belt, a water-containing tank through which said belt runs, means for depositing said material on said belt, and a trough communicating with said tank and arranged to catch surplus material spilling from the edge of said belt.
- 90 22. An apparatus for casting hot liquid material comprising a moving carrier, a container for said material, a plurality of discharge nozzles communicating with said

4
1 container and having narrow discharge slots disposed transverse to the direction of movement of said carrier, and means for successively cooling the layers of material passing from said nozzles.

5 23. An apparatus for casting hot liquid material comprising a moving belt, a container for said material, a plurality of discharge nozzles communicating with said container and having narrow discharge slots disposed transverse to said belt, means for successively cooling the material issuing from said nozzles, and means for wetting said belt.

10 15 24. An apparatus for casting hot liquid

material comprising a moving carrier, a container for said material having one or more outlets arranged to deliver said material upon said carrier, and a screen interposed between each of said outlets and the interior of said container.

15 25. An apparatus for casting hot liquid material comprising a moving carrier, a heated container for said material, and a plurality of nozzles adapted to deposit said material on said carrier, said nozzles communicating with said container at different levels respectively.

In testimony whereof I affix my signature.

JOHN L. MAUCH.
